CYLINDER ETCHING MACHINE

Charles L. Henderson, Appleton, Wis., assignor
to Paper Patents Company, Neenah, Wis., a
corporation of Wisconsin

Application August 6, 1947, Serial No. 766,805

6 Claims. (Cl. 41—9)

1

The present invention relates particularly to improved apparatus for etching intaglio or relief printing cylinders.

In intaglio printing the printing surface ordinarily comprises a smooth, metallic surfaced cylinder, usually of copper, having etched therein, symmetrically arranged ink-receiving recesses of very small area. The ink recesses throughout the printing surface are separated by line-like, unetched lands, which serve to support the doctor or scraper blade used for removing excess ink from the printing surface during the actual printing operation.

Various methods and procedures have been developed for etching printing surfaces. For example the etching machine and method disclosed in my prior Patent 2,360,676, makes possible continuous mechanical etching procedures which provide a uniformly etched surface. The etching machine and method disclosed in my co-pending application Serial No. 715,893, which was filed on December 12, 1946, and which is assigned to the assignee of the present invention, also provides an apparatus and method whereby the progress of etching a printing surface is closely controlled, so that a more uniformly etched surface having more accurate tonal quality will be produced. Both of my prior machines provide means for efficiently and accurately etching printing cylinders which are of substantially regular sizes.

In some printing processes, however, it is necessary to etch cylinders of widely varying diameters and lengths, for example, it may be necessary to etch cylinders having diameters ranging from less than about 3 inches to more than about 14 inches, and the provision of apparatus for this purpose constitutes the principal object of the present invention. This object is accomplished by the provision of an etching machine which includes means for quickly and accurately positioning the printing cylinder to be etched and means for rapidly adjusting the area which is exposed to the etching fluid. Thus, the high quality etched surface of my prior procedures may be consistently produced on irregularly sized cylinders. Other objects and advantages of the invention will be made clear upon reference to the accompanying drawings and the following description of one preferred embodiment thereof.

In the drawings,

Fig. 1 is a fragmentary, side elevational view, partially in section, of an etching machine constructed in accordance with the present invention;

2

Fig. 2 is an end elevational view taken on line 2—2 in Fig. 1;

Fig. 3 is a sectional view taken on line 3—3 of Fig. 1;

5 Fig. 4 is a sectional view taken on line 4—4 of Fig. 1;

Fig. 5 is an enlarged, sectional view taken on line 5—5 of Fig. 1;

10 Fig. 6 is an enlarged, fragmentary view taken on line 6—6 of Fig. 1;

Fig. 7 is a sectional view taken on line 7—7 of Fig. 6;

15 Fig. 8 is a fragmentary, elevational view of a modified form of air nozzle for use with apparatus of the present invention; and

Fig. 9 is a sectional view taken on line 9—9 of Fig. 8.

The etching machine illustrated in the drawings, as before pointed out, is designed, particularly, for etching printing cylinders of widely varying sizes. The etching machine generally comprises a relatively heavy frame structure, a pair of bearings, vertically adjustably supported on columns, for rotatably supporting the printing cylinder which is to be etched, means for rapidly and accurately adapting the supporting columns to printing cylinders of varying sizes, means for rotating the printing cylinder, a container for the acid or other etching fluid, means 20 for applying the fluid to the printing cylinder, and means for controlling the area on which the etching fluid acts. In the present machine, narrow, carefully directed streams of pressure air are utilized to limit the area of the cylinder subjected to the action of the etching fluid, and these air streams are adjustable so that they may be directed against the cylinder, during the etching operation, along a line which is normal to the surface of the cylinder. The surface being etched 25 comes in contact with only etching fluid and the pressure air from the air streams.

The frame structure illustrated includes a heavy rectangular frame 11 which is supported upon upright members 13. The frame members 45 11 and 13 are desirably of relatively heavy structural steel and are covered with an acid-resisting coating at all points where there is possibility of contact with the etching fluid. Suitable platforms are included on the frame 11 to provide 30 support for the driving motors and other associated apparatus. The frame 11 is enclosed by suitable plate members 14 which form a casing about the frame 11 and the elements supported thereon. Suitable hinged panels 16 are provided 35 on each end of the machine to permit access to

the mechanism which is enclosed by the casing. Flared, upwardly extending sheets 18 are attached to each end of the apparatus to prevent etching fluid from splashing onto surrounding working spaces.

An etching fluid or acid tank 15 extends longitudinally to the frame and is supported at its ends and at various points along its length, as necessary, to provide a rigid structure. The acid tank is desirably shaped as illustrated in the drawings, and has a longitudinally extending shell portion 17 having an arcuate section 19 extending for approximately 260° around the bottom of the shell. The arcuate section 19 converges to form a longitudinally extending throat 23. The ends 25 of the acid tank 15 are plane surfaces and are desirably bolted to the longitudinal shell portion 17. The acid tank ends 25 are attached to the end members of the rectangular frame 11. An acid inlet 27 is provided in the bottom of the acid tank 15, as illustrated in the drawings. The inner portion of the tank 15 and the acid inlet 27 should be covered by a suitable acid-resisting material 26 as, for example, a $\frac{1}{8}$ to $\frac{1}{4}$ inch coating of pure, black gum rubber or a suitable acid-resisting paint or cement.

A large circular portion 28 is cut out of each of the end sections 25 to provide access to the interior of the acid tank 15 for removing or servicing an impeller member 29 which is to be hereinafter described. The openings resulting from the cut-out portion are sealed by removable plate members 31 which are provided with bearings for rotatably supporting the shaft for the impeller 29. A seal between the plate members 31 and the end sections 25 of the acid container 15 is provided by extending the rubber or other acid-proof coating provided on the inner surface of the acid container 15 to a position under the plate member 31. This seal insures that the metal will not be exposed to the action of the etching fluid.

The acid, or other etching fluid, indicated at 33 in Fig. 5, is atomized and applied to the surface which is to be etched by means of the rotatable impeller member 29. The impeller 29 comprises a series of paddle members 35 made from an acid-resisting plastic, or some other acid-resisting material. The paddle members 35 are affixed to a suitable rotatable shaft 31, and one end of the shaft 31 extends through an opening in one end of the acid tank 15 for connection to a motor 39 or other rotating means. If it is desired, a curved, fixedly positioned, deflector, as shown in application Serial No. 715,893, may be used in conjunction with the impeller 29 to direct the acid spray upward against the surface to be etched.

The impeller 29 is supported for free, high speed rotation within the acid container by the bearings in the plate members 31. Desirably, the bearings for the impeller shaft 31 are provided with a suitable acid proof seal such as the pressure air seal disclosed in my application Serial No. 715,893.

The motor 39 which is used for rotating the impeller 29 is supported on a bracket 41 affixed to one of the frame uprights 43, and is connected to the impeller shaft 31 by a belt 43 and suitable pulleys 45 and 47. The impeller 29 should be rotated at relatively high speed in order to accomplish good atomization and an even distribution of the etching fluid along the surface which is to be etched. Impeller speeds upwards of about 1200 R. P. M. have been found to be satisfactory.

The acid tank 15 is surrounded by an air jacket 48 fabricated from sheet material. The air jacket 48 is shaped to conform with the shape of the acid tank 15, and is large enough to allow for the free circulation of air around the outside of the acid tank as is shown by the arrows 49. The air jacket 48 is conveniently attached to the upper end of the acid tank 15 by means of a suitable spacer-bracket and bolt assembly 50 (Fig. 5). 10 The blower 53 is adapted to be powered by a motor 55, and both the motor 55 and the blower 53 are supported on a suitable frame 57.

The air streams or blasts, which remove etching fluid from the cylinder being etched and 15 which determine the area of the cylinder subjected to the acid spray, emanate from a pair of spaced-apart, adjustably supported, longitudinally extending, air nozzles 59. The air nozzles 59 are located adjacent the outlets of the air 20 jacket 48 and form a continuation thereof. Each of the nozzles is fabricated from a pair of longitudinally extending, rigid plate members 61, desirably of acid-resisting metals which are joined together at each end by a suitable connecting 25 member 63 which closes off the ends of the plate members 61. Each of the connecting members 63 includes an outwardly extending journal section 65 which is adapted to be supported in suitable bearings on the frame 11. The connecting members 63, thus support the nozzles 59 so as to 30 permit limited rotation thereof; the connecting members 63 also determine the spacing of the opening between the longitudinally extending members 61. The outlet of each of the air nozzles 35 59 comprises a slot 67 of uniform width. Normally the width of the slot 67 is fixed, it being in the range of from about .005 inch to about .015 inch when the air pressure in the air jacket is maintained at about 4 pounds per square inch.

40 The base portion of each of the air nozzles 59 is resiliently connected to the air jacket 48 by means of an elongated, flexible connecting member 69 of rubber or the like (Figs. 6 and 7). The flexible connecting member 69 is rectangular in cross section and is proportioned so that it is wedged tightly between the side members of the air jacket 48 and the acid container 15 when in place therein. The upper end of the flexible connecting member 69 fits within the base of the air nozzle 59 (Fig. 6). Generally vertically extending holes 71 are provided in the flexible members 69 so that the pressure air from the air jacket 48 is allowed to pass freely into the nozzles 59. The resilient connection provided by the flexible member 69 permits relative angular movement between the air nozzle 59 and the air jacket 48, in response to the adjusting means which locates the nozzle 59 for cylinders of varying sizes.

The adjustment of the direction of the air 60 streams is one of the important features of the present invention. In order to permit such adjustment, a gear segment 73 is attached to each end of the outwardly extending journal sections 65 on one of the air nozzles 59 by means of 65 suitable keying members, and cooperating segments 74 are keyed to the outwardly extending journal sections 65 on the other air nozzle 59. The gear segments 73 and 74 are proportioned and disposed so that they mesh along the center line of the machine, as illustrated particularly in Fig. 3. Adjustment of the direction of the air nozzles 59 is effected by means of a longitudinally extending control rod 75 which is 70 rotatably supported on the frame 11. A pair of pinion gears 77 adapted to mesh with the two

gear segments 73 are keyed to the control shaft 75. A worm wheel 79 is also attached to the shaft 75, and this worm wheel 79 is operatively engaged by a worm 81 whose shaft 83 is rotatably journaled into a bearing 84 on the frame. An adjusting crank or knob 85 is connected to the worm shaft 83 for positioning the air nozzles 59. One end of the control shaft 75 extends adjacent the end panel 16 of the machine, and is conveniently provided with a pointer 89 for indicating the position of the air nozzles 59.

It is apparent that positioning one of the nozzles 59 will automatically position the other nozzle 59 by virtue of the intermeshing connection between the gear segments 73 and 74. The provision of uniform, adjusting torque at each end of the machine is especially desirable, as the balanced application of adjusting force insures that the air nozzles 59 will not warp and that they will deliver an even blast of air to the cylinder being etched. A suitable transparent viewing window 91 is provided in the outer end panel 16 adjacent the end of the control shaft 75 for observing the pointer 89. This window 91 may be scribed with indicating marks 93 for showing the various positions of the air nozzles 59 which correspond to normals to the surfaces of various sized printing cylinders (Fig. 2).

In order to control the level of the etching fluid 33 in the acid tank 15, an adjustable height, filling-container 95 is provided. The container 95 is vertically, adjustably fastened to a bracket 97 on the frame 11 and is connected to the inlet 27 of the acid container 15 by means of a gum rubber or other acid-resisting, flexible hose 99. In order to closely control the level of the etching fluid 33 in the acid tank 15, it is desirable to provide a constant level overflow 101 which may be connected to an acid recovery tank by means of a hose 103. All the surfaces of the filling-container 95 are covered with an acid-resisting coating. It is advantageous if one of the sides of the container is formed into a spout or guide 105 so that the etching solution may be conveniently poured from the filling container 95 when it is desired to drain the acid from the main acid tank 15.

The cylinder etching machine of the invention includes adjustable means for accommodating cylinders of widely varying dimensions and, in the particular machine shown in the drawings, this means includes an adjustable bearing support structure for the cylinder 107 which is to be etched. This structure includes two screw jack members 109 which are supported for vertical movement in suitable bearings 111 on the main frame 11. The upper ends of the screw jacks 109 terminate in a bearing support yoke 110 which is adapted to cradle the bearings in the cylinder shaft during the etching operation. The lower ends of the screw jacks 109 are threaded with low pitch threads 113, and these are connected by a suitable worm and worm wheel linkage to a hand crank 116 which simultaneously moves the two screw jacks 109 upwardly or downwardly. The linkage includes a pair of fixed bearing blocks 115, one of which is attached to each end of the main frame 11 adjacent the threaded portion 113 of the screw jacks 109. Each of the bearing blocks 115 includes a horizontally extending slot 117 in which is confined a worm wheel 119 which has a central threaded hole for operatively engaging the threaded portion 113 of the screw jack 109. A control rod 121 which extends longitudinally the main frame 11, is

5 journaled for rotatable movement in the fixed bearing blocks 115, and a pair of control worms 123 which engage the periphery of the worm wheels 119 are keyed to this control rod. The control crank 116 is connected to one end of the control rod 121 so that the position of the screw jacks 109 may be simultaneously adjusted in a vertical plane. An indicating member 125 is attached to the screw jack adjacent the hand crank 116 so that the operator may accurately position the bearing yokes 110 before the cylinder 107 is placed in the etching position. In this connection a viewing window 127 in the hinged end panel 16 is calibrated to the diameter and circumference of the cylinders being etched so as to permit the rapid and accurate pre-setting of the bearing support yoke 110.

10 The adjustment of the distance between the surface of the cylinder 107 being etched and the outlet of the air nozzles 59 is a most important adjustment in the successful operation of the etching machine of the invention. Usually a spacing of from about $\frac{1}{2}$ to $\frac{3}{2}$ of an inch will be found satisfactory in the illustrated apparatus, with the air slots that have been described. In place of the manual operation by means of the hand crank 115, hydraulic or power-actuated jacks may be used.

15 A motor 129 for rotating the cylinder 107 which is to be etched is supported on the plate or door 16 on a suitable support bracket 131. A pulley 133 on the motor drive shaft is operatively connected to a pulley 135 which is adapted to fit on the cylinder shaft by means of a belt 137. In order to rapidly adapt the equipment to printing cylinders of varying diameters it is desirable to provide a spring-biased, belt take-up arrangement which allows rapid changes in the effective length of the drive belt 137 without altering the position of the driving motor 131. In the illustrated structure this is accomplished by the provision of a fixed idler pulley 139 and a movable idler pulley 141 which is slidably engaged between a pair of generally vertically extending tracks 143 (Figs. 1 and 4). The block for the pulley 141 is connected by means of a flexible chain 145 to a sprocket 147 which is biased by means of a tensioned spiral spring 149. The entire assembly is protectively surrounded by a shield 151 which is provided with a curved central guard 153 adapted to support the belt 137 when it is not disposed around the pulley 135 on the printing cylinder 107.

20 To start the machine in operation, the acid or other etching fluid 33 is poured into the filling container 95 until the liquid level in the acid tank 15 is high enough for the impeller blades 35 to dip into the acid about $\frac{1}{4}$ of an inch at the lowest position in their arc of travel. The cylinder 107 which has a set of ball bearing rings 155 on its shaft is cradled in the yokes 110 provided for the bearings on the adjustable screw jacks 109. The height of the yokes 110 is adjusted so that the distance between the air slot 67 and the surface of the cylinder is from about $\frac{1}{2}$ to $\frac{3}{2}$ of an inch. The air nozzles 59 are then positioned so that they are normal to the surface of the cylinder 107 to be etched. Since the control means are provided with suitable indicators 25 which are calibrated in accordance with the dimension of the cylinders to be etched, the air nozzles 59 and the bearing yokes 110 may be positioned prior to cradling the cylinder shaft in the supporting yokes and the operation of changing cylinders is thus greatly expedited.

When the cylinder is in place the cylinder driving motor 129 may be energized to rotate the cylinder at the proper rate. The speed is constant. Next the air blower 53 is started and the impeller 29 is energized to atomize the etching fluid. The etching is continued until the ink-receiving recesses have been etched to the required depth, whereupon the impeller 29 is then stopped and the cylinder 167 is rotated in the air blast until it is dry.

When etching relatively short cylinders it will be found desirable to partially cover both ends of the acid tank 15 with an acid-resisting, removable baffle 157, as illustrated in Fig. 5. The baffle 157 is desirably a thin sheet of acid-resisting material which can be snapped into position in the throat of the acid tank 15 where it will be supported upon the spacer brackets 50 which are used to connect the acid tank shell 17 and the air jacket 48. In order to facilitate the removal of the baffle members 157, suitable handles 161 are provided on the upper surface thereof. This arrangement confines the discharge of the etching fluid to the length of the cylinder which is to be etched.

A modified air nozzle structure is illustrated in Figs. 8 and 9; this structure is essentially equivalent to the air nozzle 59 which has been described in the foregoing, and under certain conditions it may be preferred. In the modified air nozzle 59a the air is conducted into a longitudinally extending tube member 161 at one or both of its ends. The tube 161 is provided with a series of holes 163 which open into the lower portion of the space between a pair of conveying plate members 61a which define a longitudinally extending air slot 67a. In order to permit movement of the nozzle 59a relative to the shell 17 of the acid tank 15, a flexible air lead 165 is provided. Outwardly extending journal sections 65a are attached to each end of the tube 161 and gear segments (not shown) are keyed to the outer ends of the journal section 65a. For the purpose of providing an acid-proof seal between the acid tank 15 and tube 161, the inner lining 26 of the acid tank 15 is extended upwardly and attached to the inner nozzle plate member 61a (Fig. 8). The modified air nozzle structure 59a eliminates the need for an air jacket 48 and thereby reduces the over-all cost of the equipment.

In the foregoing, there has been described a cylinder etching machine which is capable of producing gravure cylinders of extremely high quality with a minimum expenditure of time and labor. The doctoring-off of the etching solution is rendered extremely efficient because of the provision for close and accurate spacing between the air nozzle and the surface of the cylinder, and the provision of means for directing the air blast along a line which is normal to the surface of the cylinder being etched. The indicating means which cooperate with control means for adjusting the direction of the air streams and the position of the cylinder make possible the accurate pre-setting of the apparatus for cylinders of determined sizes.

Various of the features of the invention which are believed to be new are set forth in the appended claims.

I claim:

1. In combination in apparatus for etching printing cylinders means defining a pair of spaced-apart air slots, means for supporting the cylinder to be etched adjacent said air slots, means including a source of pressure air operable

to produce streams of air which flow out of said air slots and are directed against the cylinder at spaced intervals on the periphery thereof during the operation of the apparatus, means for applying a spray of etching fluid to the surface of the cylinder in the region intermediate said air streams, means for rotating the cylinder during the etching operation, and means including an adjustable mounting for said air slots for controlling the direction of said air streams whereby said streams are directed substantially normal to the surface of said cylinder.

2. In combination in apparatus of the class described, means for supporting a cylinder which is to be etched for rotation about its longitudinal axis, means for rotating said cylinder during the operation of the apparatus, means operable to direct a spray of etching fluid against the surface of said cylinder during the operation of the apparatus, and means for restricting the surface area of said cylinder exposed to said etching fluid and for doctoring off etching fluid from the surface of said cylinder, said means including a pair of adjustably supported, spaced-apart, generally parallel air nozzles which extend longitudinally of said cylinder and through which air streams are directed against the surface of said cylinder, and a control linkage interconnected with each of said adjustably supported air nozzles for simultaneously positioning said nozzles to cause said air streams to impinge upon the surfaces of various sized cylinders along lines defined by extended radii of said cylinder.

3. In combination in apparatus of the class described, adjustable means for supporting a cylinder which is to be etched for rotation about its longitudinal axis, means for rotating said cylinder, means operable to provide a spray of etching fluid which is directed against a portion of the surface of said cylinder being etched, including an elongated tank which contains etching fluid and which has an elongated, relatively narrow throat and means for atomizing the etching fluid within said tank, and means for doctoring off etching fluid and for confining the etching fluid spray to a predetermined portion of the surface of the cylinder which is being etched, said last mentioned means including a pair of spaced-apart, elongated, horizontally extending air nozzles, means including an adjustable mounting for said air nozzles intermediate the throat of said acid tank and surface of the cylinder being etched, a strip of flexible material interconnecting each of said nozzles with said tank, a source of pressure air, and means for connecting said source of pressure air to said nozzles.

4. In combination in apparatus for etching printing cylinders of varying sizes, adjustable means for supporting the cylinder which is to be etched for rotation about its longitudinal axis, means for rotating said cylinder, means operable to provide a spray of etching fluid which is directed against a portion of the surface of said cylinder being etched including an elongated tank which contains etching fluid and which has an elongated, relatively narrow throat and means for atomizing the etching fluid within said tank, and means for doctoring off etching fluid and for confining the etching fluid spray to a predetermined portion of the surface of the cylinder which is being etched including a pair of spaced-apart elongated, horizontally extending air nozzles, means for adjustably supporting said air nozzles intermediate the throat of said acid tank and the surface of the cylinder being etched, a

supply of pressure air connected to said nozzles, control means interconnected with said nozzles for simultaneously positioning said nozzles to deliver streams of pressure air onto the surface of said cylinder, and indicating means associated with said control means, said indicating means being calibrated for varying sized cylinders whereby said nozzles can be pre-set in a position wherein said streams of air are directed along lines defined by extended radii of the cylinder being etched.

5. In combination in apparatus for etching printing cylinders of varying sizes, adjustable means for supporting the cylinder to be etched for rotation about its longitudinal axis, means for rotating said cylinder, an elongated tank which contains etching fluid positioned adjacent the surface of the cylinder being etched, said tank having an elongated, relatively narrow throat, means for atomizing the etching fluid within said tank, and means for confining the etching fluid to a predetermined portion of the area of the cylinder including a pair of spaced apart, elongated, horizontally extending air nozzles, a source of pressure air, means connecting said source of pressure air to each of said air nozzles, at least one journal section on each of said air nozzles, said air nozzles being disposed intermediate the throat of said acid tank and the surface of the cylinder being etched and being supported for hinged movement about an axis defined by said journal sections, a mechanical control linkage for positioning said nozzle including a gear attached to each of said journal sections, the gears on opposite air nozzles meshing along the center line of said tank, a control shaft which is provided with gears for meshing with the gears on at least one of said air nozzles, means for rotating said control shaft to thereby simultaneously position said nozzles to deliver streams of air onto the surface of the cylinder being etched, and indicating means associated with said control shaft, said indicating means being calibrated for varying sized cylinders whereby said nozzles can be pre-set in a position wherein said streams of pressure air are directed along lines defined by extended radii of the cylinder being etched.

6. In combination in apparatus for etching printing cylinders of varying sizes, adjustable means for supporting the cylinder to be etched

for rotation about its longitudinal axis, means for rotating said cylinder, an elongated tank which contains etching fluid positioned adjacent the surface of the cylinder being etched, said tank having an elongated, relatively narrow throat, means for atomizing the etching fluid within said tank, and means for confining the etching fluid to a predetermined portion of the area of the cylinder including a pair of spaced apart, elongated, horizontally extending air nozzles, a source of pressure air, means connecting said source of pressure air to each of said air nozzles, at least one journal section on each of said air nozzles, said air nozzles being disposed intermediate the throat of said acid tank and the surface of the cylinder being etched and being supported for hinged movement about an axis defined by said journal sections, a mechanical control linkage for positioning said nozzle including a gear attached to each of said journal sections, the gears on opposite air nozzles meshing along the center line of said tank, a control shaft which is provided with gears for meshing with the gears on at least one of said air nozzles, means for rotating said control shaft to thereby simultaneously position said nozzles to deliver streams of air onto the surface of the cylinder being etched, and indicating means associated with said control shaft, said indicating means being calibrated for varying sized cylinders whereby said nozzles can be pre-set in a position wherein said streams of pressure air are directed along lines defined by extended radii of the cylinder being etched.
